(57) **CLAIM**

The ornamental design for a display screen or portion thereof with animated graphical user interface, as shown and described.

DESCRIPTION

The file of this patent contains at least one drawing/photograph executed in color. Copies of this patent with color drawing(s)/photograph(s) will be provided by the Office Upon request and payment of the necessary fee.

FIG. 1 is a face view of a first image in a sequence of a first embodiment of a design for a display screen or portion thereof with animated graphical user interface, in color;

FIG. 2 is a face view of a second image thereof;

FIG. 3 is a face view of a third image thereof;

FIG. 4 is a face view of a fourth image thereof;

FIG. 5 is a face view of a fifth image thereof;

FIG. 6 is a face view of a sixth image thereof;

FIG. 7 is a face view of a first image in a sequence of a second embodiment of a design for a display screen or portion thereof with animated graphical user interface, in greyscale;

FIG. 8 is a face view of a second image thereof;

FIG. 9 is a face view of a third image thereof;

FIG. 10 is a face view of a fourth image thereof;

FIG. 11 is a face view of a fifth image thereof;

FIG. 12 is a face view of a sixth image thereof;

FIG. 13 is a face view of a first image in a sequence of a third embodiment of a design for a display screen or portion thereof with animated graphical user interface, in color;

(Continued)

FIG. 14 is a face view of a second image thereof;
 FIG. 15 is a face view of a third image thereof;
 FIG. 16 is a face view of a fourth image thereof;
 FIG. 17 is a face view of a fifth image thereof;
 FIG. 18 is a face view of a sixth image thereof;
 FIG. 19 is a face view of a first image in a sequence of a fourth embodiment of a design for a display screen or portion thereof with animated graphical user interface, in greyscale;
 FIG. 20 is a face view of a second image thereof;
 FIG. 21 is a face view of a third image thereof;
 FIG. 22 is a face view of a fourth image thereof;
 FIG. 23 is a face view of a fifth image thereof; and,
 FIG. 24 is a face view of a sixth image thereof.
 The appearance of the animated user interface sequentially transitions between the images shown in FIGS. 1-6, between the images shown in FIGS. 7-12, between the images shown in FIGS. 13-18, and between the images shown in FIGS. 19-24. The process or period in which one image transitions to another forms no part of the claimed design. The line-dot-line showing of a display screen or portion thereof forms no part of the claimed design. The text shown in broken line in FIGS. 14-18 and 20-24 forms no part of the claimed design.
